UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A COMPANY OF GREAT BRITAIN.

STEAM TURBINE.

1,405,092.

Specification of Letters Patent. Patented Jan. 31, 1922.

Original application filed May 4, 1918, Serial No. 232,571. Divided and this application filed October 2, 1920. Serial No. 414,301.

To all whom it may concern:

Be it known that I, KARL BAUMANN, a citizen of the Confederation of Switzerland, and a resident of Urmston, in the county of 5 Lancaster, England, have invented a new and useful Improvement in Steam Turbines, which is a division of application Serial No. 232,571, filed May 4, 1918, of which the following is a specification.

10 This invention relates to steam turbines of the axial flow type.

One of the limiting factors which determines the out-put of steam turbines of a given speed and efficiency is the maximum 15 permissible length of the moving blades in the low pressure stages. In order that the length of the low pressure blades may be kept within permissible limits, the low pressure portion of a turbine is sometimes constructed as a multiple stage, one portion of 20 the steam only acting in parallel in each section of the multiple stage, and flowing through adjacent sections thereof in opposite directions.

25 It has also been proposed to construct turbines in which the steam flowing in substantially the same direction throughout a low pressure part of the turbine is segregated into annular portions, which are expanded at the same or different rates and pass from a plurality of rows of moving blades to the exhaust.

According to the present invention, one 30 portion of the steam leaving an intermediate stage flows through a segmental part of the next succeeding row or rows of stationary guide blades and cooperating moving blades and thence to the exhaust. The remaining portion of the steam leaving the intermediate stage passes through a second segmental part of said next succeeding row or rows of blading, during which passage a small part only of its energy is transformed or abstracted, and then flows in substantially the 35 same axial direction through a further row or rows of stationary guide blades and cooperating moving blades and thence to the exhaust.

Steam turbines in accordance with this 40 invention may be constructed in a variety of ways, one of which is illustrated by way of example in accompanying drawings in which Fig. 1 is a central, longitudinal sectional view of the steam turbine, and Fig. 2 is a

cross sectional view taken on line II—II of 55 Fig. 1.

Referring now to Figs. 1 and 2, the turbine cylinder is indicated at 13 and the shaft at 14, the turbine here illustrated being of the impulse type. The steam is admitted to 60 a nozzle box 15 and thence to a plurality of rows of stationary nozzles 16, 16^a, 16^b, etc., and moving blades 17, 17^a, 17^b, etc., respectively cooperating therewith, each of the stationary blades and cooperating moving 65 blades comprising a stage. Stationary guide blades 18 are provided in a fixed diaphragm 19 extending over a segmental portion only of a row of moving blades 20, the upper portion of the segmental diaphragm 19 being provided with the stationary guide blades 32 for the passage of steam through the upper segmental portion of the moving blades 20. From the radial edges 21 of the upper portion of the diaphragm 19 a division wall or diaphragm 22 extends within 70 the exhaust casing 23 downwards, as shown, to the exhaust outlet of the turbine 24. The diaphragm 22 has a saddle-shaped surface 75 and forms a guide for that portion of the steam leaving the moving blades 17^c which passes through the stationary blades 18 and the moving blades 20 to the exhaust outlet 24, extending to and being merged into the exhaust casing at its sides as shown. 80 Diaphragm 25 containing a ring of stationary guide blades 26 is secured in the cylinder and a final row of moving blades 27 co-operating therewith is mounted on a wheel 85 on a shaft 14. The portion of the steam leaving the row of moving blades 17^c which does not pass through the segmental set of 90 guide blades 18, is directed through the stationary blades 32 and the upper segmental portion of the moving blades 20 on its way to the final row of stationary guide blades 26. As the upper segmental portion of this 95 stage is intended to pass steam from the portion of the row of moving blades 17^c to the final row of stationary blades 26 and co-operating blades 27, the guide blades 32 are so designed that the drop in pressure of the steam passing across them is as small as possible. Accordingly the guide blades 100 105 32 are designed with a large exit angle so as to pass the maximum quantity of steam for a given area of drop in pressure, and at the same time direct the steam flowing through the

moving blades 20 so that the steam will enter the latter with a minimum loss due to shocks and eddies. It is in some cases found to be advantageous to provide a diffuser for the steam which is passed through the upper portion of the moving blades 20 for the purpose of largely reconverting into pressure energy the velocity energy of the steam leaving the upper portion of the moving blades 20. Said diffuser may conveniently consist of a row of stationary blades 33 of suitable shape to give the desired diffuser effect.

The turbine may either be so designed that practically no mechanical work is obtained from the upper portion of the moving blades 20, or be so designed that a proportion of the energy is abstracted from the steam passing through the upper portion of the moving blades 20, the remaining energy of said steam being abstracted by the moving blades 27. Alternatively, the turbine may be designed in such a way that energy is imparted to the steam whilst flowing through said upper portion of the moving blades 20.

Preferably, though not necessarily, the exhaust casing enclosed below the diaphragm 22 and the rear portion of the exhaust casing which receives the steam from the final row of moving blades 27 are provided with internal guide walls such as 28, 29, 30 of the kind described either in the specification of patent application, Serial No. 123,697 filed the 4th October 1916 or of patent application, Serial No. 187,963 filed the 24th August 1917.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In an elastic-fluid turbine in which the elastic fluid is divided into two segmental portions and expanded at different rates for cooperation with a row of moving blades and means for expanding the least expanded portion for cooperation with another row of blades.
2. In an elastic-fluid turbine, a row of moving blades, means cooperating with said row to secure the division of elastic fluid passing therethrough into segmental portions and a greater degree of energy-abstraction from one portion than from the other, another row of moving blades, and means for admitting said portion of elastic fluid which has undergone the lesser degree of energy-abstraction to the latter row of blades for further energy-abstraction.

3. In a turbine, a section comprising a plurality of rows of moving blades, means for segmentally dividing the elastic fluid passing through one row of blades into a plurality of portions and for leading one of the portions to another row of blades, and fixed guide blades for the first row of moving blades, those for the portion of the elastic fluid subsequently admitted to the other row of moving blades having large outlet angles.

4. In an elastic-fluid turbine, a section comprising a plurality of rows of moving blades, fixed guide blades for admitting elastic fluid to one of said rows of moving blades, means cooperating with said row for dividing the elastic fluid discharged therefrom into a plurality of segmental portions and for conducting one of the portions for full-peripheral admission to another row of blades.

5. In an elastic-fluid turbine, a section comprising a row of moving blades, means cooperating with said row of blades for dividing the elastic fluid passing therethrough into a plurality of segmental portions, fixed guide blades for admitting elastic fluid to said row of blades, another row of moving blades, and means for conducting one of said segmental portions of elastic fluid for admission to the last-named row of blades.

6. In an elastic-fluid turbine, a low-pressure section comprising a plurality of rows of moving blades, fixed guide blades for admitting elastic fluid to one of said rows of moving blades, and means cooperating with said row for dividing the elastic fluid discharged therefrom into a plurality of segmental portions, leading one of the segmental portions to the exhaust, and leading another segmental portion for admission to another row of moving blades.

7. In an elastic-fluid turbine, a low-pressure section comprising a fixed diaphragm, segmental rows of guide blades carried by said diaphragm, one row having relatively large outlet angles, a row of moving blades adapted to receive elastic fluid from said guide blades, means cooperating with the moving blades to segregate the elastic fluid discharged thereinto by said row of blades having large outlet angles from that discharged by the other row, and another row of moving blades adapted to receive elastic fluid which has passed through said row having large outlet angles.

8. In a steam turbine of the axial flow type, means for passing a portion only of the steam leaving an intermediate stage through a segmental part of the next succeeding row or rows of stationary guide blades and cooperating moving blades, and means for passing another portion of the steam through a second segmental part of said next succeeding row or rows of blading, the stationary guide blades of the first men-

tioned segmental part being designed to convert a different proportion of the pressure energy of the steam flowing through them into velocity energy than the guide blades 5 of the second mentioned segmental part.

9. In a steam turbine of the axial flow type, means for passing a portion only of the steam leaving an intermediate stage through a segmental part of the next succeeding row or rows of stationary guide blades and cooperating moving blades and thence to exhaust, and means for passing the remaining portion of the steam through 10 a second segmental part of the said next succeeding row or rows of blading and through a further row or rows of stationary guide blades and cooperating moving blades and thence to exhaust, said stationary guide blades of the first segmental part being de- 15 signed to convert a greater proportion of the pressure energy of the steam flowing through them into velocity energy than the guide blades of the second mentioned segmental part. 20

10. In a steam turbine of the axial flow type, means for directing all of the steam through intermediate stages, and directing a portion only of the steam through a segmental part of the next succeeding row of 25 blading and the remainder of the steam through a second segmental part of the said next succeeding row of blading and means for converting into velocity energy different proportions of the pressure energy of the 30 steam passing through said two segmental parts. 35

11. In a steam turbine of the axial flow type, means for directing all of the steam through intermediate stages, means for passing a portion only of the steam leaving an intermediate stage through a segmental part 40 of the next succeeding row or rows of sta-

tionary guide blades and cooperating moving blades and thence to exhaust, means for passing the remaining portion of the steam 45 through a second segmental part of said next succeeding row or rows of blading and through a further row or rows of stationary guide blades and cooperating moving blades and thence to exhaust, and means comprising 50 a diffuser for partly reconverting into pressure energy the velocity energy of the steam leaving the second mentioned segmental part before it passes to the said further row or rows of blades. 55

12. In a steam turbine of the axial flow type, means for passing a portion only of the steam leaving an intermediate stage through a segmental part of the next succeeding row or rows of stationary guide 60 blades and cooperating moving blades and thence to exhaust, and means for passing the remaining portion of the steam through a second segmental part of the said next succeeding row or rows of blading and then 65 through a further row or rows of stationary guide blades and cooperating moving blades and thence to exhaust, said stationary guide blades of the first segmental part being designed to convert a greater proportion of the 70 pressure energy of the steam flowing through them into velocity energy than the guide blades of the second mentioned segmental part, and means comprising a diffuser for partly reconverting into pressure energy 75 the velocity energy of the steam leaving the second mentioned segmental part before it passes to the said further row or rows of blades.

In testimony whereof I have hereunto 80 subscribed my name this 28 day of September, 1920.

KARL BAUMANN.
